ABSTRACT: This disclosure relates to tufting apparatus of the type for producing pile fabrics such as carpets and the like. The disclosure further teaches a novel use of a novel apparatus for producing a pile fabric wherein efficient use is made of the yarn so that maximum usage of the yarn is utilized for the pile surface and a minimum for the backstitch.

MULTIPLE-PILE-TUFTING MACHINES, METHOD AND PRODUCT

BRIEF DESCRIPTION OF THE INVENTION

This invention is directed to a novel tufting apparatus for producing a novel pile fabric. More particularly, the tufting apparatus of the invention includes a novel arrangement of needle and looper or hook combinations with a fabric feed which brings about the desired novel results. In general, the backing fabric is fed in a first direction relative to the needle or bed plate surface and then reversed in a direction over a second surface of the bed plate so that, during each needle stroke, the needle will penetrate said backing fabric at spaced points thereof. After penetration of the backing fabric by the needle, a hook grasps the yarn loop passed through the backing fabric by the needle and holds it until the needle is returned back through the backing fabric. A change in the relative position of the backing fabric, the needles, and the hooks is brought about so that upon the next succeeding penetration of the needle, the penetration point will be laterally spiced and downstream from the first penetration point. Before penetration of the needle at the second penetration point, the yarn is draped over an upper or second looper mechanism so that when the needle penetrates at the second point, an upper loop will be formed on the top surface of the backing fabric over the second looper or hook, and a third loop will be formed upon penetration by the needle at the second point by the lower or first hook grasping the loop carried by the needle, as in the case of the first penetration point. Thus, it will be seen that by the novel mechanism provided and the operation thereof, three pile loops are provided for each two penetrations of the needle so that efficient use of the yarn is accomplished for the pile face of the fabric with a minimum amount of the yarn being used for the backstitch in proportion to the amount on the pile face.

Accordingly, it is one objective of the invention to provide a novel and improved tufting apparatus.

It is another objective of the invention to provide a novel and improved tufting apparatus wherein efficient use is made of the yarn for the pile face of the fabric.

It is a further objective of the invention to provide a novel and improved method of forming a pile fabric.

It is still another objective of the invention to provide a novel and improved pile fabric.

It is still an additional objective of the invention to provide a novel and improved apparatus and method for producing a pile fabric wherein for each two penetrations of the needle through the backing fabric, three pile loops are formed on the pile face of the fabric.

Other objectives and advantages of the invention will be best understood when reading the following detailed description with the accompanying drawings. It should be understood, however, that the invention is set forth in its preferred embodiment and is described in sufficient detail so as to enable those skilled in the art to readily understand the inventive concept herein and the advantages thereof.

BRIEF DESCRIPTION OF THE DRAWINGS

FIG. 1 is an axial sectional view of a portion of a tufting machine illustrating the tufting components therein;

FIG. 2 is a sectional view of a portion of the tufting machine illustrating FIG. 1 taken in the direction looking from the left-hand side of FIG. 1;

FIG. 3 is a partial, enlarged perspective view showing the tufting components of the tufting machine, illustrated in FIG. 1;

FIGS. 4A-4F illustrate the sequential steps of forming the stitches formed by the mechanism of the above figures;

FIG. 5 is a partial, enlarged perspective view illustrating the stitch formed by the mechanism of FIGS. 1-3;

FIG. 6 is a partial, sectional view showing another embodiment of the invention;

FIG. 7 is a view similar to FIG. 6 but in perspective and showing still another stitch formation capable of being produced by the mechanism of the invention; and

FIG. 8 is a partial, sectional view showing another embodiment of the invention.

DETAILED DESCRIPTION OF THE INVENTION

With reference to the drawings, in particular FIG. 1, there is illustrated a portion of the tufting machine, including a tufting machine head 10 supported on a suitable frame and in which is journaled a driven main shaft 12. A plurality of eccentrics 14 are fixed to the main shaft, only one of which is shown and which eccentric is connected by a connecting member to a push rod 16 mounted vertically for endwise reciprocation in the lower portion of the head 10. Connected to the lower end of the push rod 16 is a needle bar support 18 in which there is slidably carried a needle bar 20 which is supported for relative lateral movement with respect to the needle bar support 18 in a manner which will be more fully described below. The needle bar 20 carries a plurality of yarn carrying needles 22 which are each threaded with a yarn Y and which needles are preferably aligned laterally of the machine. Thus, it will be seen that during rotation of the main shaft 12, the push rod 16 will be reciprocated vertically for imparting reciprocation to the needles so that the needles penetrate the backing fabric F which is passed thereunder to project loops of yarn therethrough.

Backing fabric F through which the loops pass conventionally passes under the needles in a plane, which is substantially perpendicular to a plane including the path of needle travel, from one side of the machine to the other. Reference may be made to the patents to Beasley Nos. 2,840,019 and 2,857,867 which illustrate fabric feed means of this type.

Briefly, feed rolls are positioned at one side of the machine for drawing the backing fabric from a supply roll and pass it over a bed plate and under the needles to the other side of the machine where another feed roll draws it to an area where the carpet is gathered for further processing. In the present machine, however, the machine bed plate carries a needle plate 24 which in the preferred embodiment, illustrated in FIG. 1, is preferably at a slight angle relative to the plane including the needle path and has a corner portion 26 or conical-shaped portion at the side adjacent to the needles over which the backing fabric F is drawn and wherein the direction of travel of the backing fabric F is reversed. It will be seen, therefore, in FIG. 1 that the backing fabric initially travels in one direction toward the needle 22 and over the needle plate 24 and then in a direction away from the needle 22 to a takeup roll, not illustrated. The function of the needle plate 24 will be more fully described hereinafter. As shown in FIG. 3, the needle plate 24 has a plurality of cutout portions or openings 28 through which the needles pass during penetration of the backing fabric F as the backing fabric is passed around the corner portion 26 of the needle plate 24. This is to permit the yarn carrying needles 22 to penetrate through two sides of the backing fabric F without interference from the needle plate 24.

A plurality of lower hooks or loopers 30 are provided below the needle plate 24 to intercept a loop of yarn passed through the backing fabric F by the needles 22 and to hold the same during return of the needle to its raised position, there being one such hook 30 for each needle 22. The hooks 30 are supported in a bar 32 which in turn is suitably connected to an oscillating shaft 34 which is rocked back and forth by suitable drive means connected to the main shaft 12 of the machine in a well-known manner. In a conventional tufting machine wherein the backing fabric is passed straight under the needles 22 from one side of the machine to the other, each time the needle penetrates backing fabric F with a loop of yarn, the hook 30 intercepts the same to hold it as the needle is raised and the fabric is then advanced and the process is repeated so that straight lines of loops are produced by each needle and its

75

associate hook mechanism. As will be better understood hereinafter, the present mechanism functions significantly differently in this respect than a conventional tufting machine.

As further illustrated, suitably fixed to the machine head 10 is a support mechanism 36 which fixedly carries at its lower end a plurality of upper hooks or loopers 38, each of which has a curved portion or hood portion 40 which preferably curves around the corner portion 26 of the needle plate 24. With reference to FIG. 2, it will be seen that each upper hook 38 is positioned between adjacent needles 22 and adjacent lower hooks 30. As the needles reciprocate, they will pass between adjacent pairs of upper hooks 38 and in close proximity to their lower hooks 30 wherein the yarn will be intercepted, as explained above.

With reference to FIGS. 1 and 2, the needle bar 20 is supported for lateral movement relative to the needle bar support 18 and also relative to the backing fabric F. In order to accomplish this, the needle bar 20 is connected by a shaft 42 to a link and eccentric or cam mechanism 44 which is driven by a shaft 46 from a transmission unit 48. The transmission unit 48 is preferably driven by a chain and sprocket, illustrated at 50, from the main shaft 12 of the machine. This device is commonly known in the tufting art as a sliding needle bar mechanism and reference is made to U.S. Pat. No 3,026,840 for a more detailed description thereof.

In FIGS. 5A through 5F, there is illustrated in diagrammatic form some of the steps in the sequence for forming the novel stitch and fabric produced by the apparatus described above. In FIGS. 4A and 4B, the needle 22, carrying the yarn Y, is reciprocated so that it passes on one side of the upper looper 38 and penetrates the backing fabric F at two separated points. In other words, the needle 22 first passes through the backing fabric face on the upper surface of the needle plate 24 then passes through that portion of the backing fabric F which is traveling in the opposite direction below in the needle plate 24. As illustrated in FIG. 4B, the lower looper 30 is rocked into position for intercepting the yarn Y as the needle 22 reaches its lowermost position. As the needle 22 is raised, the lower looper 30 holds the yarn Y to form a fixed loop 52 in a well-known manner. The lower looper 30 holds the loop 52 until the needle 22 has substantially reached its uppermost position. The illustration in FIG. 4D shows that the backing fabric F has been advanced and the needle 22 has been moved laterally so that during its next downward stroke, it passes the yarn Y through two separated points in the fabric F and on the other side of the upper looper 38. Again, as the needle 22 reaches its lowermost position, the lower looper 30 will intercept the yarn Y to form another loop, 54, which is laterally displaced from the loop 52 and also displaced downstream from the loop 52 with reference to the direction of fabric feed. Referring to FIGS. 4D and 4E, collectively, it will be seen that between the first and second penetrations of the needle 22 to form the loops 52 and 54, a loop 53 is formed as the needle 22 was removed from the backing fabric F after its first penetration and shifted laterally during advancement of the backing fabric F. This loop 53 is formed from one limb of the yarn Y, extending from the needle eye which is draped over the upper looper 38 during lateral shifting of the needle 22. It will be seen, therefore, with reference to FIGS. 4A-4E that during each cycle, including two penetrations of the needle through the backing fabric, three loops are formed on the pile surface side of the backing fabric F and include two loops 52 and 54, formed by the combination of the needle 22 and lower looper 30, and the diagonal loop 53, formed through the relative movement of the needle with respect to the upper looper 38.

Referring to FIG. 5, several cycles of operation of loop formation are illustrated therein in exaggerated form. As will be apparent from the inspection of FIG. 5, a relatively large amount of yarn appears on the lower or pile surface side of the fabric with a relatively minimum amount of yarn being used in the backstitch. Further, it may be seen that two parallel rows of loops 52 and 53 have been formed with each row being interconnected by the diagonal loop 53. The novel stitch and

fabric formed by the method and apparatus of this invention is a significant advancement in the tufting art, particularly insofar as carpet production is concerned, since maximum amount of coverage is provided for the face of the fabric with a minimum amount of yarn being expended for the backstitch. As is well known in the carpet production field, the usage of yarn is one of the major contributing factors in the cost of manufacturing carpet. Therefore, if the nonusage part of the yarn, or the backstitch, can be minimized, substantial savings in production will be realized. This is accomplished through the present invention, and furthermore, this result is accomplished through use of substantially the same machine effort as that required by conventional tufting machines.

FIGS. 6 and 7 illustrate further embodiments of the invention where instead of initiating relative lateral movement between the needle, the fabric, and the loopers, the stitch formation is produced in a straight line. Instead of using a laterally reciprocating needle, reciprocating upper loopers 56 and 58 in FIGS. 6 and 7, respectively, are provided with the upper loopers reciprocating back and forth in a direction parallel to the fabric feed on the upper face of the needle plate 24. Referring first to FIG. 6, the upper looper 56 is reciprocated into position for intercepting a limb of the yarn Y carried by the needle 22 during each penetration of the needle 22 through the backing fabric F in the manner described above. This produces a straight line of loops 60 formed by the combination of the needle 22 and the lower looper 30 during each penetration of the needle 22 and a series of interconnecting loops 62 formed by the combination of the needle 22 and the reciprocating upper looper 56. The interconnecting loops 62 are formed by the successive penetrations of the backing fabric F passing over the upper surface of the needle plate 24 and extend between the first penetration points of the needle 22 during each of its needle penetration strokes, as in the case of the embodiment described above. After formation of the stitch, illustrated in FIG. 6, it has been found that the interconnecting loops 62 have a tendency to lean to either side of the straight line of loops 60 to thus enhance the overall yarn coverage between the adjacent rows of loops 60. Again, the fabric formed, having the stitch illustrated in FIG. 6, has the same advantage as that described above in relation to the first embodiment.

In FIG. 7, the stitch and fabric formed therein are substantially the same as that in FIG. 6, but it illustrates the variation which can be brought about by changing the speed of the fabric feed relative to the cycle of operation of the tufting mechanism, including the needle and loopers. The upper looper 58 is substantially the same as that illustrated in FIG. 6 and operates in virtually the same manner. It has been found that by varying the speed of operation of the components of the stitch forming mechanism and the speed of the fabric feed, novel variations in stitch formation can be provided while still maintaining the advantages set forth above.

As described above in relation to the first embodiment illustrated in FIGS. 1-3, the fabric and stitch formation, formed by this mechanism, is in part produced by initiating relatively lateral movement between the needle, the loopers, and the fabric. The mechanism, described in FIGS. 1-3 for carrying out this purpose, was that referred to as a sliding needle bar mechanism, wherein the needle was shifted laterally relative to the other components. It should be understood, however, that the invention, illustrated in FIGS. 1-3, is not restricted to the use of a sliding needle bar mechanism. Referring to FIG. 8, illustrated therein, is another embodiment of the invention, which shows a novel mechanism for producing a substantially similar result to that shown in FIGS. 1-3. Instead of providing a shifting or sliding needle bar, the needle bar 64 in FIG. 8 is a fixedly attached to the push rod 16, as illustrated. The upper looper 38 with its support 36, instead of being fixed to the machine frame 10, is slidably carried in a support bar 66 so that the upper looper mechanism may be moved laterally relative to the needles 22 in a manner which will be described hereinafter. The needle plate 24 of FIG. 6, instead of being

stationary, is slidably disposed in a support mechanism 68 in a manner similar to that described in FIG. 1 with relation to the sliding needle bar 20. The upper looper mechanism 38 with its support 36 is connected by suitable means, not shown, such as a U-shaped bar or the like to the needle plate 24 at the outer ends thereof and may be in turn connected to a mechanism for initiating a lateral movement thereof such as the transmission 48, the push rod 42, the eccentric 44, and the transmission shaft 46, as shown in FIG. 2. Thus, it will be seen that in lieu of a sliding needle bar, the upper looper and needle plate may be shifted laterally so that the backing fabric F and the upper looper 38 will be disposed in the same relative position with respect to the needle 22 during each cycle described in relation to the first embodiment.

It will be seen from the above-detailed description that a novel tufting apparatus has been described which through its method of operation produces a novel tufting stitch and fabric which has significant advantages over conventional tufting production. Most significant of these advantages lies in the maximum utilization of the yarn for the pile face of the fabric in comparison to the minimum requirements of yarn for the backstitch. Further, due to the relatively dense yarn coverage provided on the pile surface, it is possible to use relatively wider gauge parts in the tufting mechanism and achieve results comparable in coverage density to that achieved in finer gauge conventional tufting machines. The machine of the present invention preferably is modified from that illustrated for purposes of describing the invention. For example, in the preferred construction the machine head, including the push rods and needles, is inclined downwardly away from the vertical and the needle plate is inclined upwardly at its open end from the horizontal. The loopers are disposed so as to function in the proper manner with the associated inclined needles and needle plate. By thus inclining the tufting components, easy access is had to these components for threading, adjustments, repairs, replacements, etc. It is the applicants' intention that the invention described herein is not limited by the above description, but only by the claims as they appear hereinafter.

Having thus set forth the nature of the invention, what we claim herein is:

1. A tufting machine for producing a pile fabric including a needle adapted to penetrate a base fabric during each stroke thereof for carrying a yarn through the base fabric, a base fabric support means, means for feeding a base fabric in a first direction adjacent to first surface of said support means and in a second direction adjacent to a second surface of said support means such that during feeding of the base fabric said needle will penetrate the base fabric at longitudinally spaced points during each stroke thereof, first looper means cooperating with said needle and its yarn to form a loop extending from one of the points of penetration of said needle, second looper means cooperating with said needle and its yarn to form a loop extending from another of the points of penetration of said needle.

2. A tufting machine as recited in claim 1 wherein said needle and said base fabric support means are relatively inclined at an angle of less than 90°.

3. A tufting machine as recited in claim 1 wherein a substantial portion of said first looper means is disposed adjacent to said first surface of said base fabric support means and said second looper means is disposed in the region of the opposite side of said base fabric support means.

4. A tufting machine as recited in claim 3 wherein said first looper means includes a curved portion which extends around one end of said base fabric support means and toward said second surface of said base fabric support means.

5. A tufting machine as recited in claim 3 wherein a plurality of needles and first and second loopers are provided and each first looper being disposed between adjacent needles and second loopers.

6. A tufting machine as recited in claim 3 wherein said first looper means is reciprocable in a plane parallel to a plane including the path of travel of said needle.

7. A tufting machine as recited in claim 1 further comprising means for initiating relative lateral movement between said needle, said looper means, and the base fabric.

8. A tufting machine as recited in claim 7 wherein said means for initiating relative lateral movement includes a laterally displaceable needle bar supporting said needle for lateral and reciprocable movement, and means connected to said laterally displaceable needle bar for initiating lateral movement thereof with said needle.

9. A tufting machine as recited in claim 7 wherein said base fabric support means and one of said first and second looper means is laterally displaceable whereby during lateral displacement of said base fabric support means and said one looper means the base fabric and said one looper means will be shifted laterally relative to said needle and the other of said looper means.

10. A tufting machine as recited in claim 9 wherein the major portion of said first looper means is disposed substantially wholly adjacent said first surface of said base fabric, and said first looper means is laterally displaceable.

11. A method of forming a pile fabric comprising feeding a base fabric in a first direction for a portion of its travel and changing the direction of feed for another portion of its travel, penetrating the base fabric with a yarn-carrying needle adjacent to that portion of the base fabric wherein its travel is changed so that the needle penetrates the base fabric at longitudinally spaced first and second points in the base fabric, holding the yarn adjacent to one face of the base fabric during removal of the needle from the base fabric to form a loop of

15 yarn on said one face, positioning a loop-retaining element between the needle and the yarn extending from the base fabric prior to the next penetration stroke of the needle, advancing the base fabric, again penetrating the base fabric with the yarn-carrying needle, holding the yarn adjacent to said one surface of the base fabric during removal of the needle from the base fabric whereby during each two penetration strokes of the needle two spaced loops are formed at spaced points in the base fabric and are interconnected by a third loop extending between said spaced points.

12. A method of forming a pile fabric with pile forming components including a yarn-carrying needle and first and second loop-forming elements, said method steps comprising: feeding a base fabric in a first direction for a portion of its travel and substantially reversing the direction of travel of the

45 base fabric for a second portion of its travel, penetrating the base fabric with the yarn-carrying needle adjacent to the vicinity wherein the travel of the base fabric is reversed such that the needle penetrates the base fabric at spaced first and second points in the base fabric, holding the yarn with one of the first and second loop forming elements during removal of the needle from the base fabric to form a loop extending from one surface of the base fabric, intercepting a portion of the yarn carried by the needle with the other of said first and second loop-forming elements during the next penetration stroke of the needle to form a loop extending between

50 the penetration points in the base fabric, penetrating the base fabric a second time with the needle at a point downstream of the first penetration point with respect to the direction of travel of the base fabric such that the needle again penetrates the base fabric at spaced first and second points in the base fabric, holding the yarn with one of the first and second loop forming elements during removal of the needle from the base fabric to form another loop extending from said one surface of the base fabric whereby for each two penetration strokes of

55 the needle two loops will be formed on said one surface of the base fabric by said yarn carrying needle and said one of said first and second loop forming elements and a third loop will be formed on said one surface of the base fabric by said yarn carrying needle and the other of said first and second loop forming elements.

13. A method of forming a pile fabric as recited in claim 12 further comprising, initiating relative lateral movement between said yarn carrying needle, said base fabric, and at least one of said first and second loop-forming elements between penetration strokes of said needle.

14. A method of forming pile fabric as recited in claim 13 further comprising, initiating lateral movement of the other of said first and second loop retaining elements and said base fabric with respect to said needle.

15. A method of forming a pile fabric as recited in claim 13 further comprising, initiating lateral movement of said needle with respect to said base fabric and said first and second loop forming elements.

16. An apparatus for producing textile fabrics such as carpet or the like including means for passing a yarn through a base fabric, a base fabric support means for supporting a base fabric, guide means for maintaining a transverse fold in the base fabric during travel over said base fabric support means, said base fabric support means and said guide means being disposed relative to said means for passing a yarn through the base fabric such that the yarn is passed through a portion of the transverse fold in the base fabric, first loop forming means for grasping the yarn after passing through the base fabric, to form a loop extending from one surface of the base fabric, and second loop forming means for forming a loop on said one surface of said base fabric and extending between successive points in the base fabric where the yarn is initially passed through the transverse fold in the base fabric.

17. An apparatus as recited in claim 16 further comprising means for initiating relative movement between said second loop forming means, said means for passing a yarn through a base fabric and the base fabric.

18. An apparatus as recited in claim 17 wherein said means for initiating relative movement includes means for initiating lateral movement of said second loop forming means and the

30

base fabric.

19. An apparatus as recited in claim 17 wherein said means for initiating relative movement includes means for initiating lateral movement of said means for passing a yarn through a base fabric.

20. An apparatus as recited in claim 17 wherein said means for initiating relative movement includes means for reciprocating said second loop-forming means.

21. An apparatus as recited in claim 16 wherein said second loop forming means includes a loop forming element having a body portion and a hook portion at one end thereof, and said hook portion being disposed such that it extends around the transverse fold adjacent to one surface of the base fabric.

22. A pile fabric comprising a base fabric having rows of pile loops extending from a first surface thereof to form a pile surface and rows of backstitch on a second surface thereof opposite from said first surface, said rows of pile loops including a first row of pile loops with each pile loop thereof extending from a point in said base fabric, a second row of pile loops disposed parallel to said first row with each pile loop in said second row extending from a point in said base fabric spaced laterally from the points in said first row, and interconnecting pile loops extending from said first surface and bridging said first and second rows of pile loops.

23. A pile fabric as recited in claim 22 wherein each said interconnecting pile loop extends between a point in each of said first and second rows disposed between adjacent pile loops in each of said first and second rows.
